SIGN

Filed Jan. 29. 1931

W. L. Lowry, INVENTOR

BY *Victor J. Evans*

ATTORNEY

UNITED STATES PATENT OFFICE

WALLACE LEON LOWRY, OF JOHNSON CITY, TENNESSEE

SIGN

Application filed January 29, 1931. Serial No. 512,150.

This invention relates to signs, and its general object is to provide a rotary sign adapted to be wind actuated in an easy manner, due to the fact that friction of the rotary parts has been reduced to a minimum and ample lubricating means therefor has been provided, with the result slight wind pressure will be sufficient to cause the sign to rotate.

10 A further object of the invention is to provide a rotary sign including suitable supporting and elevating means, which is capable of being erected in an expeditious manner, the sign in its entirety being formed from metal and including interfitting parts that are slidably mounted and held associated in a manner whereby the sign will efficiently operate for a prolonged period of time without fear of damage thereto by excess wind and heavy storms.

15 Another object of the invention is to provide a sign that is constructed in a manner to provide wind vanes that in no way obstruct the advertising matter carried by the sign, but at the same time assure proper rotation.

20 A still further object of the invention is to provide a sign of the character set forth, that is simple in construction, inexpensive to manufacture, easy to install and extremely efficient in operation and service.

25 This invention also consists in certain other features of construction and in the combination and arrangement of the several parts, to be hereinafter fully described, illustrated in the accompanying drawing and specifically pointed out in the appended claims.

30 In describing my invention in detail, reference will be had to the accompanying drawing wherein like characters denote like or corresponding parts throughout the several views, and in which:

35 Figure 1 is a fragmentary front elevation of the sign which forms the subject matter of the present invention.

40 Figure 2 is a sectional view taken approximately on line 2—2 of Figure 1, looking in the direction of the arrows.

45 Figure 3 is a sectional view taken approx-

imately on line 3—3 of Figure 1, looking in the direction of the arrows.

50 Referring to the drawing in detail, the reference numeral 1 indicates a frame which includes diverging portions having secured thereto legs 2, through the instrumentality of suitable securing means such as bolt and nut connections 3. The frame and legs provide a tripod formation and act in the capacity as the base or supporting structure for 60 the sign.

The frame includes a sleeve 4 having formed with its upper portion a collar from which extends the diverging portions, and these portions have their lower ends bent at 65 an angle upon themselves for integral connection with the sleeve as shown in Figure 1.

65 Secured in the sleeve through the medium of screw bolts is a pipe element 5. The pipe element rises from the sleeve and has fixed 70 in its upper end a grease cup 6 of the spring pressed ball valve variety, for the purpose of lubricating bearing members 7 and 8, and the pipe element 5 is provided with openings 9 to allow for the passage of grease to 75 the balls of the bearing members, the openings 9 being arranged in alignment with the balls as clearly shown in Figure 2. The innermost ball races of the bearing members are secured to the pipe element, while the 80 outermost ball races are carried by upper and lower strips 10 which act in the capacity as the top and bottom of the sign, and the outermost ball races are secured to the strips by 85 angle brackets 11. By this construction, it will be apparent that friction between the pipe element and the sign proper has been reduced to a minimum due to the bearing members and the manner of lubricating the 90 same.

95 The strips 10 have formed with their longitudinal edges thereof, outwardly extending parallel disposed flanges 12 and these flanges are accommodated in channel grooves 13 provided on the longitudinal edges of the face plates 14 and 15, the latter being slidably mounted on the flanges when assembling the sign.

100 The face plates 14 and 15 are identical and formed with one of the end edges thereof is

a relatively wide flange 16, while the opposite edge is provided with a relatively narrow flange 17. These flanges are provided with openings to accommodate bolt and nut connections 18, and the flange 16 of the face plate 14 is secured to the flange 17 of the face plate 15, while the flange 16 of the face plate 15 is secured to the flange 16 of the face plate 14, these flanges being arranged in contact-
5 10 15 20 25 30 35 40 45 50 55 60 65 70 75 80 85 90 95 100 105 110 115 120 125 130

ing engagement as shown in Figure 3, and provide what may be termed wind vanes, due to the fact that they are arranged at right angles with respect to the face plates, with the result rotation of the sign member on its bearings is assured, with minimum air currents.

The strips 10 are held in operative relation through the instrumentality of braces 19 which are arranged in converging relation 20 with respect to each other, and have right angle bent ends, the lower ends being secured to the lower strip 10 adjacent the ends thereof, while the upper ends of the braces 19 are secured to the upper strip 10 adjacent the 25 center thereof, and upon opposite sides of the angle brackets 11. Cooperating with the braces 19 are braces 20 which are vertical and also have right angle bent ends secured to the upper and lower strips 10 adjacent the 30 outer ends as shown by dotted lines in Figure 1. The strips 10 and braces 19 and 20 provide a skeleton frame for the sign proper.

From the above description and disclosure of the drawing, it will be obvious that I have 35 not only provided a rotary sign that will actuate with minimum wind currents, but the sign can be installed in an easy and expeditious manner, due to the fact that the parts can be quickly assembled and secured accordingly through the medium of bolt and nut connections and other necessary fastening means as shown.

While the sign can be made ornamental in various ways, I prefer to have strips such 45 as indicated by the reference numeral 21, with coiled ends and arranged in alignment, and supported on the upper surface of the upper strip 10.

It is thought from the foregoing description that the advantages and novel features of my invention will be readily apparent.

I desire it to be understood that I may 70 make changes in the construction and in the combination and arrangement of the several parts, provided that such changes fall within the scope of the appended claims.

What I claim is:

1. A rotary sign comprising supporting means, a pipe element secured to the supporting means and rising therefrom, a frame mounted for rotation on said pipe element, upper and lower strips included in said frame, face plates having channels to slidably accommodate portions of the upper and lower strips, and flanges formed with the face plates to provide wind vanes. 75 80 85 90 95 100 105 110 115 120 125 130

2. A rotary sign comprising supporting means, a frame mounted for rotation on said supporting means, bearings between the frame and said supporting means, means for lubricating said bearings from a common source, strips included in said frame, flanges formed with said strips and extending vertically therefrom, face plates having channels thereon to slidably accommodate the flanges and relatively wide and narrow flanges formed with said face plates and arranged in a manner whereby the narrow flange of one face plate cooperates with the wide flanges of the other face plate, with the flanges secured together accordingly to provide wind vanes. 95

3. A wind operated sign comprising a supporting standard, a rotatable head carried by the standard including an open rectangular frame having a top wall, a bottom wall, and end walls, marginal flanges formed on the longitudinal edges of the top and bottom walls, and side sign plates having guide flanges on their longitudinal marginal edges receiving the flanges of the top and bottom walls, and means for locking the sign plates together against accidental displacement from the frame. 100 105 110 115 120 125 130

In testimony whereof I affix my signature.
WALLACE LEON LOWRY.
